TOWEL

Rosalie Forster, Long Island City, N. Y.

Application September 29, 1949, Serial No. 5,228

Term of patent 7 years

(Cl. D92—26)

To all whom it may concern:

Be it known that I, Rosalie Forster, a citizen of the United States, residing at Long Island City, New York, in the county of Queens, and State of New York, have invented a new, original, and ornamental Design for a Towel, of which the following is a specification, reference being had to the accompanying drawing, forming part thereof.

In the drawing:

The figure is a face view of one half of a towel, showing my new design. The full width of the towel is disclosed horizontally and the design unit is repeated vertically in proper relation to complete the towel.

I claim:

The ornamental design for a towel, as shown and described.

ROSLIE FORSTER.
